DESIGN FOR AN APRON

Louis Rogow, New York, N. Y., assignor of one-half to Maurice Mitrani and Vitalis Alcoumre, both of New York, N. Y.

Application February 10, 1937, Serial No. 67,565

Term of patent 3½ years

To all whom it may concern:

Be it known that I, Louis Rogow, a citizen of the United States, residing at New York, in the county of Kings and State of New York, have invented a new, original, and ornamental Design for an Apron, of which the following is a specification, reference being had to the accompanying drawing, forming part thereof.

The figure represents a plan view of an apron, showing my new design.

The characteristic feature of my design re-

sides in the combination on the apron as shown of individual breast flaps laced together at their abutting edges, and connected at their upper edges by a neck piece of translucent material, translucent material also serving as the skirt trim.

I claim:

The ornamental design for an apron as shown and described.

LOUIS ROGOW.
